F. R. BARBOUR

TENT

Filed April 15, 1926

Inventor:
Fred R. Barbour,
By *Wm. H. Ward*
Attorney.

UNITED STATES PATENT OFFICE.

FRED R. BARBOUR, OF LOS ANGELES, CALIFORNIA.

TENT.

Application filed April 15, 1926. Serial No. 102,257.

This invention relates to tents and more particularly to tent supports.

The general object of the invention is to provide a tent support which will effectively 5 support a tent without the use of a center pole.

A more particular object is to provide a tent support of the character stated which may be readily collapsed and folded up compactly for storage or shipping.

10 A further object is to provide means for supporting a tent with or without a center pole.

Other objects will appear as the description progresses.

15 My invention is illustrated in the annexed drawing which forms a part of this specification, and in which:

Fig. 1 is a transverse vertical section of a tent supported by my support.

20 Fig. 2 is a vertical sectional view of a tent taken at right angles to Fig. 1, with certain elements of my support removed and showing the remaining element and a center pole in full lines connected thereto in the center

25 thereof for supporting the tent, and showing said center pole in dotted lines connected to one side of said remaining element for supporting the tent while my support is being set up in place or taken down.

30 Fig. 3 is an enlarged vertical section of the bridge element of my support.

Fig. 4 is a fragmentary vertical sectional view of my support taken on line 4—4 of Fig. 3.

35 Fig. 5 is a side view of the bridge element of my support folded up for storage or shipping.

Corresponding reference numerals designate the same parts in all the views.

40 In the drawing 1 and 2 indicate the side walls, 3 and 4 the front and rear walls; and 5 the top of a flat-top tent; there being a top frame 6 upon which the top 5 rests, which frame comprises a pair of upwardly bowed

45 rafters 7 and 8, upon which the front and rear edges of the top 5 rest, and a peak bar 9 upon which the peak of the top rests, said bar being connected at its ends to the rafters 7 and 8 midway between the ends of said rafters and

50 extending under the top from the front to the rear of the tent. The parts above described are common to a standard flat top tent.

My support comprises a saddle element 10, secured to the under side of the peak bar 9 in

55 the center thereof; a bridge element 11 which

fits in said saddle, and a pair of poles 12 and 13, upon the upper ends of which poles rest the ends respectively, of said bridge element, the lower ends of the poles resting upon the ground or floor of the tent, and the poles 60 being located within the tent adjacent the side walls 1 and 2 thereof respectively.

The saddle element 10 comprises a saddle 14 and a pair of arms 15 and 16 extending forwardly and rearwardly respectively, with relation to said saddle. The saddle element may be made of a single piece of sheet metal bent downwardly at right angles at 17 and 18 to form the upper horizontal wall 19 and the depending vertical side walls 20 and 21 of 70 the saddle, and then bent upwardly from the lower edges of said side walls in the form of angle braces 22 and 23, and then bent forwardly and rearwardly from the upper ends of said braces respectively to form the arms 75 15 and 16.

The saddle element 10 is provided with a central opening 24, in the upper saddle wall 19, and with an opening 25 in the forward arm 15. The saddle element is secured to the under side of the peak bar 9 by means of screws 26 and 27 driven through apertures 28 and 29 in the arms 15 and 16 respectively, with the saddle 14 facing downwardly and the upper saddle wall 19 and the arms 15 85 and 16 resting against the under side of said bar, and with the openings 24 and 25 in registration with sockets 30 and 31 in the under side of the bar, the socket 30 and aperture 24 being located midway of the ends 90 of the bar 9 in the center of the top 5 and the tent, and the socket 31 and aperture 25 being located forwardly of the center of the top and tent.

The bridge element 11 comprises a head 95 35 and a pair of bridge beams 36 and 37. The head 35 is channel shaped, being formed with an upper wall 38 and with depending side walls 39 and 40, the under side of the upper wall being inclined slightly downwardly as indicated at 41 and 42 from a point 43 midway of the ends of the head to its ends respectively. The inner ends of the bridge beams 36 and 37 fit within the channel of the head 35 between the side walls 39 and 40, the beam 36 being secured to the upper wall 38 against the inclined under surface 41 thereof by screws 44, whereby the beam is positioned at an inclination corresponding to the inclination of said surface 41. The 100 110

upper and inner ends of the beams 36 and 37 are hinged together on their under sides by a hinge 45, so that the beam 37 may be swung up against the under surface 42 of the upper wall 38 into operative position at an inclination corresponding to said surface, or swung downwardly against the beam 36 in collapsed position for storing or shipping. (See Fig. 5.)

The head is formed with a projection 46 on its upper side in the center thereof. Openings 47 and 48 are provided in the outer ends of the beams 36 and 37 respectively. The head 35 fits within the saddle 14, with the upper wall 38 of the head against the upper saddle wall 19 and the projection 46 in the opening 24, and with the side walls 39 and 40 of the head against the side walls 20 and 21 of the saddle, the engagement of the projection 46 with the opening 24 holding the head 20 in the saddle against longitudinal displacement therein. The openings 47 and 48 receive the pins 49 and 50 in the upper ends of the poles 12 and 13, whereby the ends of the bridge beams 36 and 37 are prevented from 25 sliding off said poles.

My support may be readily removed by withdrawing the pole pins 49 and 50 out of the openings 47 and 48 in the beams 36 and 37 and withdrawing the head 35 from the saddle 14. The bridge element 11 may then be folded up compactly by swinging the beams 36 and 37 together on their hinges 45 as shown in Fig. 5.

The saddle element 10 may be secured to the under side of the peak bar 8 of any flat top tent without interfering with the support of the tent by means of a center pole, if desirable.

When the side poles 12 and 13 and the bridge element 11 of my support are removed, one of said poles 12 or 13 may be used as a center pole for supporting the tent by inserting the pin 49 or 50 on the upper end of the pole through the opening 24 in the upper wall 19 of saddle 14 and into the socket 30 in the peak bar 9.

My support may be installed in the tent or removed therefrom without taking down the tent. This may be done by supporting the tent with one of the poles 12 or 13 upon inserting the pin 49 or 50 of the pole in the opening 25 and socket 31, as shown in dotted lines in Figs. 2 and 4. When the tent is supported in this manner there is more room in the tent back of the pole than there is when the pole is placed in the center of the tent as shown in Fig. 2.

Metal straps 51 and 52 are extended around the ends of the bridge beams 36 and 37 respectively, and are provided with apertures 53 and 54 which coincide with the lower and upper ends respectively of the openings 47 and 48 and take the wear off the pole pins 49 and 50, so that said pins will not wear out the openings 48 and 49. Said straps 51 and 52

are secured to the beams 36 and 37 by screws 55.

While I have shown a preferred embodiment of my invention in the accompanying specification and drawing, it will be understood that I may change or modify the same within the scope of the appended claims without departing from the spirit thereof.

What I claim is:

1. In a tent, in combination with the top frame of the tent, a saddle secured to the under side of said frame, a bridge element comprising a head, a pair of beams hinged together at their inner ends within said head and one of said beams being secured to said head, said head being adapted to fit in said saddle, a pair of poles located adjacent the side walls of the tent and within the tent, upon the upper ends of which poles the ends of said beams rest.

2. In a tent, in combination with the top frame of a tent, a saddle secured to the under side of said top frame and provided with an aperture, a bridge element comprising a head, a pair of beams hinged together at their inner ends within said head and one of the beams being secured to the head, a projection on the upper side of said head, said head being adapted to fit in said saddle with said projection fitting within the aperture in said saddle, and positioning the head within the saddle, and a pair of poles located within the tent adjacent the side walls thereof upon the upper ends of which the ends of said beams are supported.

3. In a tent, in combination with a top frame provided with means for supporting a tent thereon as a side pole tent and also provided with means to engage means for supporting a tent as a center pole tent and including a saddle element secured to the under side of said frame, and provided with two apertures, one of said apertures being in the center of the top and the other aperture being at one side of said center, said frame having sockets aligned respectively with said apertures, a bridge element being adapted to fit in said socket element, and poles adapted to be placed within the tent adjacent the side walls thereof upon the upper ends of which poles the bridge element is supported, there being pins on the upper ends of said poles, so that the pin on one pole may be fitted in either of said apertures and the socket aligned therewith to enable said pole to support the tent when the bridge element and the other pole are not in use.

4. In a tent, the combination of a top frame and means thereon adapted for engagement with lateral supporting means for providing a side pole tent and also adapted for engagement with a central supporting means for providing a center pole tent.
